UNITED STATES PATENT OFFICE.

WILLIAM A. JAMESON, OF NIAGARA FALLS, NEW YORK.

DESIGN FOR A HANDLE FOR SPOONS, FORKS, OR SIMILAR ARTICLES.

44,313.

Specification for Design.

Patented July 8, 1913.

Application filed April 23, 1913. Serial No. 763,169. Term of patent 7 years.

To all whom it may concern:

Be it known that I, WILLIAM A. JAMESON, a citizen of the United States, residing at Niagara Falls, in the county of Niagara and State of New York, have invented a new, original, and ornamental Design for a Handle for a Spoon, Fork, or Similar Article, of which the following is a specification, reference being had to the accompanying drawing, forming part thereof.

Figure 1 represents the reverse side of the design; and Fig. 2 the obverse side.

I claim:

The ornamental design for a handle for a spoon, fork or similar article as shown.

WILLIAM A. JAMESON.

Witnesses:

B. ELLISON,
MILDRED DICKINSON.
